UNITED STATES PATENT OFFICE.

CHARLES W. ROGERS, OF BALTIMORE, MARYLAND.

HARNESS-SADDLE PAD.

SPECIFICATION forming part of Letters Patent No. 368,115, dated August 9, 1887.

Application filed April 17, 1886. Serial No. 199,182. (No model.)

To all whom it may concern:

Be it known that I, CHARLES W. ROGERS, a citizen of the United States, residing at Baltimore, in the State of Maryland, have invented certain new and useful Improvements in Harness-Saddle Pads, of which the following is a specification.

My invention relates to an improvement in gig-saddle pads, and is illustrated in the accompanying drawings, which show the parts in the various successive stages of manufacturing.

Figure 1 is a view of the pad-cover for the two sides of the saddle. Fig. 2 is a view of the pad-spreader. Fig. 3 is a cross-section, on a larger scale, of the pad-spreader, showing how it is bent on a longitudinal central line to facilitate sewing the second reed-cover to the flap, as seen in Fig. 12. Fig. 4 is a view of the pad-spreader and the felt pasted thereto on the side where the longitudinal central crease has been cut. Fig. 5 is a view of the pad cover and spreader quilted together, the felt being between the two. Fig. 6 is a cross-section, on a larger scale, of pad-cover, pad-spreader, and felt quilted together, as in Fig. 5. Fig. 7 is an outer side view of the pad-cover and the two reed-covers stitched thereto with reeds. Fig. 8 is an inner side view of the flap. Fig. 9 is a view of the pad-cover, reed-covers, spreader, and flap, and shows the first reed-cover sewed to the flap. Fig. 10 is a cross-section, on a larger scale, of the parts embraced in Fig. 9, and shows the position of said parts when sewing together the first reed-cover and flap. Fig. 11 is a view of the parts, showing both reed-covers sewed to the flap. Fig. 12 is a cross-section, on a larger scale, of the parts embraced in Fig. 11, and shows the position of said parts when sewing together the second or last reed-cover and flap. Fig. 13 is a view of the gig-saddle or harness-saddle complete.

The letter *a* designates the pad-cover—that pad which confines the stuffing and rests upon the animal's back. It will be seen at the upper end, *a'*, the pad-cover is narrower than it is farther down, and these ends of the two pad-covers are united by a seam, *b*. The pad-spreader *c* consists of pasteboard or other suitable material of similar character. This is cut of such breadth that it will, when flat,

spread the pad-cover *a* over the row of stitches *k* at each edge, which secures the reed-covers *f f'* and flap *I*. A peculiarity of this pad-spreader, and one which works out a useful result, is that on one side it has a longitudinal central crease, *c'*. This may be made by making a slight cut in the surface with a point of a knife. By means of this crease or cut *c'* the spreader, which is of stiff material, may be bent on a longitudinal line, as seen in Fig. 3 and also in Fig. 12, whereby its breadth is so much lessened that it can be got out of the way, and thus facilitate the sewing the stitches *k* which unite the second or last reed-cover and flap. The felt, *d*, is pasted to the pad-spreader *c* on that side where the crease or cut *c'* has been made. (See Fig. 4.) The felt, of uniform thickness, covers the middle and lower end of the spreader. These parts and the pad-cover *a* are then united by quilting *e*. (See Figs. 5 and 6.) A strip of leather is then folded to form reed-cover *f f'* and to inclose a reed, *g*. Two such reed-covers are united by stitches *h* to the pad-cover *a*, on its outer side. (See Fig. 7.) One reed-cover, *f*, (see Figs. 9 and 10,) is then placed against the inner surface of the flap *I* and secured by a row of stitches *k* placed between the reed and the row *h* of stitches. In order to unite the second or last reed-cover and flap the pad and its spreader *c* must be bent on a longitudinal line, (see Fig. 12,) so that when the reed-cover *f'* is placed against the inner surface of the flap *I* there will be room for the needle to make the row of stitches *k*.

It will now be readily understood that the longitudinal bend in the pad and spreader, that was made to facilitate sewing the last row *k* of stitches, can be reduced by flattening the pad down. For this purpose I use a tool called a "slicker," which is rubbed over the surface of the pad-cover. The formation of the pad-pocket is then complete, and the spreader *c*, being flat, serves its proper purpose, as before stated. The pad-pocket up to this point is stuffed or filled with the thin felt, *d*, at the middle and therefrom to the lower end. It now remains only to stuff the upper end or thick part, *l*. This may be done in any suitable way. I provide a special way, however, which will now be described.

As already stated, the two pad-covers *a* at

- the outset are united by a seam, *b*, which leaves the seam-edges of the material turned inward. This produces a neat smooth appearance at the crotch-point *m* of the saddle. To secure 5 this neat appearance, therefore, a half-oblone notch, *n*, (see Fig. 9,) is made at the upper end of each flap *I*. These ends of the two flaps abut and produce on top of the saddle an oblong opening, *n'*. (See Fig. 11.) Hair or other 10 pad material may then be inserted through the opening *n'* to produce the thick part *l* of the pad. Finally, a cross-row of stitches, *o*, is made through the flap and pad-cover at each 15 side of the said opening.
15 The top opening, *n'*, is covered by the metal part *p* of the saddle.
Having described my invention, I claim and desire to secure by Letters Patent of the United States—
20 1. The method of making harness-saddle pads, consisting in first stitching the reed-cover on one side of the pad to the flap, then

bending the spreader, which has a longitudinal cut for readily bending the same, then stitching together the last reed-cover and flap, 25 as shown and described.

2. A harness-saddle having its two pad-covers *a* united at their upper ends by a seam, *b*, whose edges are turned inward, and having on top through the flap an opening, 30 *n'*, for the insertion of pad material, as set forth.

3. An improved harness-saddle pad consisting of a pad-cover, a flap, reed-covers, a spreader having a longitudinal crease or cut, 35 and a lining, substantially as shown and described.

In testimony whereof I affix my signature in the presence of two witnesses.

CHARLES W. ROGERS.
